UNITED STATES PATENT OFFICE

171,632

LIGHT PROJECTOR

Joseph G. Atwood, Wauwatosa, and Philip B. Clark, South Milwaukee, Wis., assignors to McGraw Electric Company, Milwaukee, Wis., a corporation of Delaware

Application May 28, 1953, Serial No. 25,237

Term of patent 14 years

(Cl. D48—20)

To all whom it may concern:

Be it known that we, Joseph G. Atwood and Philip B. Clark, citizens of the United States, and residents, respectively, of Wauwatosa, in the county of Milwaukee and State of Wisconsin, and of South Milwaukee, in the county of Milwaukee and State of Wisconsin, have invented a new, original, and ornamental Design for a Light Projector, of which the following is a specification, reference being had to the accompanying drawing, forming a part hereof.

Fig. 1 is a perspective view of a light projector showing our new design; and

Fig. 2 is a top plan view thereof.

The dominant features of our new design are shown in solid lines.

We claim:

The ornamental design for a light projector, as shown and described.

JOSEPH G. ATWOOD.

PHILIP B. CLARK.
